UNITED STATES PATENT OFFICE.

WILLIAM SPARKS, OF JACKSON, MICHIGAN, ASSIGNOR TO THE SPARKS-WITHINGTON COMPANY, OF CLEVELAND, OHIO, A CORPORATION OF OHIO.

VALVE-CONTROLLED SUCTION LINE.

Application filed January 17, 1922. Serial No. 529,994.

To all whom it may concern:

Be it known that I, WILLIAM SPARKS, of Jackson, in the county of Jackson, in the State of Michigan, have invented new and useful Improvements in Valve-Controlled Suction Lines, of which the following, taken in connection with the accompanying drawings, is a full, clear, and exact description.

This invention relates to a new and improved valve-controlled suction line and is here disclosed in connection with a liquid elevating and feeding device as illustrative of one structure to which the invention may be applied.

It has long been known that the size of the opening leading from the manifold of the engine into a vacuum gasoline feeding device is limited by the amount of auxiliary mixture drawn from the vacuum system that an engine can stand, and not effect its operation when operating at a slow speed. The usual small opening, or orifice, is suitable and efficient for raising fuel at slow speed with nearly closed throttle, because the vacuum in the engine manifold is exceedingly high at that time. On long hard pulls or at high speed, the vacuum is very low and the time required to create a vacuum in the vacuum tank and piping to the rear supply tank sufficient to raise fuel is too long a period at these times when the engine is consuming an excessive amount of fuel, and even after it starts to raise the fuel, it is slow in raising it due to the fact that the area of the orifice is quite small compared with the area of the pipe through which the fuel is being raised.

A vacuum system having this small orifice is efficient at most throttle openings, but fails when the vacuum in the manifold is very low, and the object of this invention is to effect a variation in the size of the opening constituting a communication between the vacuum tank and the manifold of the engine, to effect a more efficient and rapid operation of the vacuum tank at low vacuum, without effecting its normal operation under high vacuum.

Other objects and advantages will appear from the following description, taken in connection with the accompanying drawings, in which:

Figure 1 is a top plan view of the vacuum tank.

Figure 2 is a vertical sectional view of the same.

Figure 3 is a slightly enlarged sectional view of the vacuum line connection to the tank.

Figure 4 shows a slightly modified form of device in which the controlling valve is located in a two-part nipple separate from the vacuum tank.

The structure of the vacuum tank proper is substantially the same as that disclosed in my co-pending application, Serial No. 482,261, filed July 2, 1921, and comprises an elevated tank —1— having a suitable connection by pipe —2— with a primary fuel tank, a second pipe connection through pipe —3—, with any source of suction as the manifold of the engine, and a third connection as through a pipe (not shown) with the carburetor. The elevated tank —1— comprises a sheet metal tubular body —5— preferably cylindrical in form and having its lower end closed by an end wall —7—. This tubular body is preferably divided into two chambers —9— and —10— by an annular transverse wall —11— having a pair of axially extending substantially concentric flanges —8—, the outer flange tightly fitting within the tubular body portion and secured thereto in any suitable manner, as by soldering, welding and the like, while the inner flange is reinforced and the reinforcement internally threaded and adapted to adjustably receive an externally threaded nipple —13— forming a means of communication between the chambers —9— and —10—.

The nipple —13— may, as shown, have an upper plate-like portion —12— resting upon the upper surface of the partition —9—. However, any suitable construction may be utilized for connecting the nipple —13— with the partition —11— so as to constitute an airtight joint.

The nipple —13— is, as shown, preferably closed at its bottom by transverse wall and is provided adjacent said wall with a lateral opening —14— through which fluid may discharge from the nipple into the chamber —10—. The communication between the chamber —9— and the chamber —10— through the nipple —13— and opening —14— is normally free and substantially unrestricted. To accomplish this effect and at times close such communication so that

vacuum may be produced in the upper chamber to an extent sufficient to elevate the liquid fuel thereto, a valve —15— is provided, pivoted at —17— adjacent the lower end of the nipple —13— and formed with a counter-arm or counter-weight —16— adapted to normally hold such valve in open position so that communication between said chambers is normally free and open, permitting free passage of liquid fuel from the upper to the lower chamber, or reversely, as conditions may require.

The nipple —13— is preferably provided with a guide for the stem —19— of the float —20— which is adapted to pass through said guide and downwardly into the interior of the nipple —13— and at certain predetermined positions of the float —20— contact with a pin or projection —18— rigidly connected to the valve —15— and extending through the opening —14— into the interior of the nipple —13— and into line with the stem —19— of the float, which moves through the guide. With this construction, the float positively moves the valve to closed position when that condition is desirable.

In the construction shown, the float stem —19— actuates a valve —23— adapted to close the passageway communicating with the nipple —3— and which leads to any suitable source of suction. The operation of the float, therefore, positively controls the source of suction, and positively closes the valve —16— when the conditions in the chamber —9— require those particular operations to effect the best result.

The fitting —3— is carried in any suitable way by cover plate —8— which forms a closure for and is connected to the upper end of the tubular body —5— in any suitable manner, as that shown. The cover plate is closed, except for the fitting —3—, the fitting or pipe —2— and the air, or atmospheric inlet —21—.

The atmospheric inlet —21— is controlled by a valve —22— which valve in turn is actuated indirectly by and in accordance with the movements of the float. The operation of the structure so far as the related nature of the suction and atmospheric valves are concerned, is that the suction valve is closed by the float when the atmospheric valve is opened. When the suction valve closes, the atmospheric valve —22— is opened and the vacuum in the upper chamber —9— is neutralized and the valve —16— by the gravity of its counterweight is moved to open position, to provide free communication between chambers —9— and —10— and permit the free discharge of fuel from the chamber —9— to the chamber —10— through the opening —14—.

As the liquid level falls in the chamber —9—, the float moves downwardly and opens

the communication with the nipple —3— and with the source of suction. When the float has moved downwardly a sufficient distance, the lower end of the float stem —19— contacts with the projection —18— and closes the valve —15—. The chamber —9— then fills, or partially fills with liquid fuel, due to the production of vacuum therein, and the valve —15— remains closed until such time as the valve —23— closes communication with the nipple —3— and the air valve —22— opens to admit atmospheric pressure into the upper chamber —9—. As soon as this takes place, the counter-weight, or counter-arm —16— opens the valve —15— and permits communication between the chambers —9— and —10—, so that the liquid discharges into the chamber —10—, from which it is supplied to the vaporizing device by gravity. The chamber —10— is maintained under atmospheric pressure at all times by means of a pipe —51— which may as shown, extend upwardly through the chamber —7— and communicate with the air vent —21—.

The valve operating mechanism illustrated for controlling the suction and air inlet ports consists of the levers —25— and —26— carrying valves —23— and —22— respectively, and having their inner ends pivoted upon a journal —33— carried by the stem —19— and moving therewith. The outer ends of the levers are pivoted with a limited sliding connection upon bosses —27— and —28—, respectively, by means of pins —29— and —30— movable in slots —31— and —32— respectively. The outer ends of the levers are connected by springs —36— which snap the valves to their extreme positions when the journal —33— is moved to the opposite side of a straight line connecting the pivotal axes of the outer ends of the levers. This effects a sudden closing of the valve —15— as well as sudden actuation of the suction and air valves.

It will be obvious that the construction so far described is operative in the ordinary manner to effect fuel feeding from a low level tank to a carburetor, and the construction described is illustrative of one to which my invention is applicable, and various and other constructions of vacuum tanks embodying different character of snap-over mechanism and different characters of valves controlling communication between the upper and lower chambers may be used.

The particular invention here disclosed in combination with a vacuum tank of the character here described, consists in placing in the vacuum or suction line —3— a suitable valve —34—, three substantially equivalent assemblages of which are illustrated in Figs. 2, 3 and 4, respectively.

The valve is confined in a chamber —39— formed in various ways and of greater diam-

eter than the valve, and of greater height than the valve to permit the passage of air around the valve and longitudinal movement of the valve in the chamber for the purpose hereinafter described. This valve —34— is provided with a relatively small central or longitudinal opening —38— which constitutes the normal communication between the manifold of the engine and the upper chamber of the vacuum tank, due to the fact that upon ordinary high vacuum, the valve —34— is immediately sucked into air-tight contact with the lower portion of the nipple section —36— so that the central conduit or aperture —38— constitutes the only means of communication between the vacuum line and the upper chamber —9— of the vacuum tank.

This valve is provided in its lower surface with a series of radially or laterally extending grooves or channels —40— leading to the central aperture —38— so as to permit communication between the outer portions of the chamber —39— and the aperture —38— and thereby the chamber —9— of the tank. When the valve —34— rests in contact with the upper flat portion of the plate —35—, which condition exists at low vacuum, so that the communication at low vacuum between the engine manifold and the chamber —9— is not only by means of aperture —38— but through the space around the valve —34— and through the channels —40— in the valve and thereby to the chamber —9—, so that at lower vacuum, the vacuum is created in the chamber —9— with much greater rapidity than as the communication were permitted alone through the aperture —38—. This increase in the size of the means of communication between the manifold of the engine and the chamber —9— at low vacuum tends to effect a more equal and uniform elevation of fuel from the main tank to the chamber —9— at all engine speeds and all degrees of vacuum in the manifold in that it permits low vacuum to withdraw from the chamber —9— a large volume of air in a short time thereby producing the required vacuum for elevating fuel and comparing favorably with the vacuum produced by high vacuum withdrawing air through a comparatively small orifice.

It will be obvious that the valve —34— is of sufficient weight so that under the low vacuum where it is desired to permit an increase in the size of the communicating passageway between the manifold and the tank —9—, the valve will not be raised from its seat by such vacuum but is not of a weight which will prevent it being immediately sucked into contact with the lower surface of the nipple section —36— at high vacuum, or at those vacuums where the size of the orifice is sufficient to effect an adequate vacuum and thereby adequate supply of fuel to

the tank —9—, or to the carburetor of the engine.

It will be obvious that the valve is automatically actuated by gravity, and the vacuum in the vacuum line leading to the manifold, but the weight of the valve may be such as to effect a substantially predetermined operation so as to feed fuel in a sufficient and desired amount to the carburetor at all engine speeds and under all degrees of vacuum.

In each of the constructions, the chamber —39— is formed in a somewhat different way. In Fig. 2, one nipple section —52— is fitted within the section —53— and has a threaded relation with it and forms with the disk —54— the chamber —39—. In Fig. 3, the section —36— is threaded into the cover —8— and with the disk —35— forms the chamber —39—.

In Figure 4, a slightly modified form of structure is shown in that the valve instead of being of cup-shape, as shown in Figures 2 and 3, is a substantially solid cylinder, having a passageway —38— therethrough with the same radial channels —40— as disclosed in connection with the valve —34—. With this construction, the valve —34— is positioned between the two nipple sections —41— and —42— which may, as shown, be threaded together, the lower nipple section being adapted for threaded engagement with the cover of the tank.

The construction of the valve shown in Figures 2 and 3 is perhaps preferable in that the side portion of the valve controlling the suction line moves into and out of the hollow interior of the valve without effecting its operation, thereby economizing space.

It will be obvious that altho I have shown my invention as applied to a fuel feeding device, yet such disclosure is merely illustrative of a particular practical application of my invention and that I do not desire to limit myself therefor to any particular structure of apparatus with which my invention may be assembled, as it may be used and applied in connection with any structure utilizing a suction line, particularly where the suction is of a varying and non-uniform character.

I claim:

1. In a device of the class described, a suction line, having a chamber, a valve in said chamber of less width than the chamber and of less height than the chamber, said valve formed with an opening extending longitudinally therethrough and with radial channels at one end extending from the edge to said opening.

2. The combination with a suction line having a valve chamber provided with upper and lower valve seats, of a suction and gravity-actuated valve in said chamber, and capable of bodily movement therein, and

- having a comparatively small conduit therethrough, said valve normally resting by gravity upon the said lower valve seat so that said conduit permits passage of air 5 through the suction line to the extent of the capacity of the conduit, and means for permitting the passage of additional air through the suction line when the valve rests upon said lower seat.
- 10 3. The combination with a suction line having a valve chamber provided with upper and lower valve seats, of a suction and gravity-actuated valve in said chamber and capable of bodily movement therein, and having a comparatively small conduit therethrough, said valve normally resting by gravity upon the said lower valve seat so that said conduit permits passage of air through the suction line to the extent of the 15 capacity of the conduit, means for permitting the passage of additional air through the suction line when the valve rests upon said lower seat, the said valve cutting off the said means permitting the passage of additional air through the suction line when the valve is drawn by suction into seating relation with the upper valve seat to thereby restrict the passage of air through the suction line to the amount capable of passing 20 through said conduit.
4. The combination with a suction line having a chamber formed with oppositely disposed seats, of a valve in said chamber of less width than the chamber, and of less 25 height than the chamber and movable bodily in said chamber into contact with either of said seats, said valve formed with a conduit extending longitudinally therethrough and with a passageway leading from said conduit to the periphery of said valve.
- 30 5. The combination with a suction line having a chamber formed with oppositely disposed seats provided with oppositely dis-
- posed valve seats, of a suction and gravity-actuated valve in said chamber and movable 45 bodily in said chamber into contact with either of said seats, and of less height than the chamber, said valve formed with a conduit extending longitudinally therethrough and with a passageway leading from the 50 conduit to the exterior of the valve.
6. The combination in a suction line of a valve chamber having oppositely disposed seats, and a conduit leading from each of said seats, of a gravity and suction-actuated valve in said chamber, said valve formed with a comparatively small conduit extending therethrough and constituting a continuous means of communication between the two first-named conduits and a passageway 55 in the valve forming an additional means of communication between the two first-named conduits when the said valve is seated by gravity.
7. The combination in a suction line of a valve chamber having oppositely disposed seats, and a conduit leading from each of said seats, of a gravity and suction-actuated valve in said chamber, said valve formed with a comparatively small conduit extending 60 therethrough and constituting a continuous means of communication between the two first-named conduits and a passageway 65 in the valve forming an additional means of communication between the two first-named conduits when the said valve is seated by gravity, but constituting no means of communication between said two first-named conduits when the said valve is seated by suction.
- 75 In witness whereof I have hereunto set my hand this 31st day of December, 1921.
- WM. SPARKS.
